HANDICAP COMPUTER

Ralph Walsh, Los Angeles, Calif.

Application February 17, 1941, Serial No. 379,184

2 Claims. (Cl. 235—61)

This invention relates to a method and apparatus for computing the handicap of a player of any game, in which the players make a score or count, and while the invention may be practiced in connection with any game, it is described in the following specification as applied to the game of golf.

It is a common practice to compute a golf player's handicap on the basis of the total score in his last ten games played, the handicap usually being a certain percentage of the total for the ten games. And, of course, this entails an enormous amount of computing to maintain the golfer's handicaps up to date.

In some clubs, the handicap is based on the total score of the lowest ten scores of the last thirteen games played.

One of the objects of my invention is to provide a simple apparatus and method of operating the same, which will enable such handicaps to be readily computed, and maintained substantially automatically, that is to say, without necessitating the continual taking of the percentage of the ten-game total, or any number of games selected.

Further objects of the invention will appear hereinafter.

The invention consists in the novel method and the combination of parts of apparatus to be described hereinafter, all of which contribute to produce an efficient apparatus and method for computing handicaps.

In the drawing:

Fig. 1 is a front elevation of the scoreboard and apparatus carried thereby, partially in section, with certain parts broken away.

Fig. 2 is a vertical section through the indicator mechanism taken about on the line 2—2 of Fig. 3.

Fig. 3 is a vertical cross-section through the mechanism taken about on the line 3—3 of Fig. 2.

Fig. 4 is an enlarged fragmentary longitudinal section taken through the dials that indicate a player's single score, that is, one game or round of eighteen holes, for example, and particularly illustrating the means for controlling its dials, and also the dials of the counter mechanism that carries the total of the last ten games played, or other total selected as a basis.

Fig. 5 is also a fragmentary view and may be regarded as a section taken about on the line 5—5 of Fig. 2 upon an enlarged scale, and particularly illustrating the means I may employ for driving the handicap indicator at a reduced speed from the counter mechanism.

Fig. 6 is a section taken about on the line 6—6 and further illustrating the parts shown in Fig. 5.

Fig. 7 is a fragmentary section of a diagrammatic nature, illustrating a common form of carrying mechanism that may be employed for carrying between the dials.

Fig. 8 is a longitudinal section through the dials of the counter, and particularly illustrating how the rotations of the unit wheel of the single score indicator, may be imparted to the handicap indicator.

In practicing the invention, I provide a score board 1 having a scale 2 with progressively ascending numbers running from one up to ten, and located respectively over "boxes" 3 at which the player's scores for the selected games are shown by means of removable panels 4 carrying digits substantially as indicated. These panels 4 are preferably slid into place from the right end, and are retained by horizontal rails or cleats 5.

At the right and in line with the player's game score panels 4, the score board is provided with a window 6 at which is displayed the faces of the dials 7 and 8 indicating the golfer's handicap; and still further to the right I provide a similar window 9 at which the faces of dials 10 and 11 are displayed. The dials 7 and 8 are shown at the left of the indicating mechanism shown in Fig. 2, and the dials 10 and 11 are shown at the right in Fig. 2.

The dials 10 and 11 and their associated parts constitute a "single score" indicator S, while the dials 7 and 8 and their associated parts constitute the handicap indicator H. Between these two indicators and on a common shaft with them is the counter T, the dials of which are set up to indicate the player's total score for the selected number of his games last played, for example, ten. The counter T has a unit dial 12, a tens dial 13 and a hundreds dial 14.

The three indicators are mounted in a suitable casing 15 at the back of the score board 1.

In addition to the dials 7 and 8, the handicap indicator may have two dials 16 and 17. All the dials of all the indicators have ten digits running from 0 to 9, and the dials all carry over to each other from right to left through carrying wheels 18 mounted loosely on a common fixed arbor 19.

The numbers on the face of dial 10 are carried on a friction-tight rim 10a, and the dial rim 10a has a projecting milled flange 10c that projects out through the back of the casing 15 (see

Fig. 3) to enable it to be touched with one's fingers to rotate the rim 10a to set up the golfer's presently made score. The dial 8 is set by means of a thumb-head 20 rigid on a tubular shaft or sleeve 21, and having a longitudinal slot 22 receiving a pin 23 on the dial 11. The inner end of the sleeve 21 has a clutch member 24 that is normally in operative connection with a corresponding clutch member 25 on the hub of the unit's dial of the counter T. A spring washer 26 normally holds this clutch 24, 25, closed.

The unit's dial 12 of the counter effects a direct drive to the unit's wheel 17 of the handicap indicator H, and for this purpose it is formed with a tubular sleeve 27, the far end of which could be directly connected to the unit's dial 17 if the handicap is always to be an even percentage of the total for ten games.

However, as some clubs may desire to compute the handicap as 1½% of the total for the games, or use some other uneven percentage, then I prefer to provide a reduction gear mechanism 28 driven by a pinion 29 on the end of sleeve 27. Through this reduction gearing a clutch 30 drives the unit's wheel 17.

It will be evident that if the reduction gear is not used, a direct connection could be effected, with a tubular sleeve from the pinion 29 to the clutch 30.

The dials are all held against shifting along their arbor 15a where necessary, by means of stop fingers 31 projecting out from the carrier shaft or arbor 19.

The carrier wheels 18 are of a type common in calculating machines. A three-toothed hub extension 32 cooperates with a cylindrical face 33 of the unit's wheel to hold a six tooth gear 34 in fixed engagement with the teeth of a carrier gear 34 on the ten's dial (see Fig. 4). At each revolution of the unit's dial a single tooth 35 projecting laterally from the unit's dial, engages one of the teeth of the six-tooth gear, and rotates the carrier gear 18 through one-third of a revolution, which rotates the ten's dial through one-tenth of a revolution. A slot 36 is provided in the cylindrical face 33 to permit one of the teeth of the three-toothed hub to pass through when the carrying movement is being effected.

The reduction gearing 28 includes an arm 37 suspended on arbor 15a and having a yoke 38 at its lower end embracing a hub 39 on one of the pinions 40 of the reduction gear train. This arm 37 carries a duplex pinion 41 secured to it by a machine screw 42. This duplex pinion forms part of the reduction gear train.

If it is necessary to change the ratio of the reduction through the reduction gear, this can be effected by providing additional threaded sockets such as socket 42a (see Fig. 5) to which the pin 42 may be moved. This, of course, would involve the providing of a new set of gears of different diameters for the gear train.

The thumb heads 20 corresponding to the different score lines are located at the right edge of the score board (see Fig. 1) and should be enclosed under a removable cover 43 that should be kept locked.

In using this apparatus, it should be understood that there are two phases for it. The first phase is when the golfer is making his first ten scores, or other scores that are to be selected as a basis for computing the handicap. A panel 4 is put in for each day, indicating his score for that particular day or round of the course.

As soon as the ten selected score panels 4 are

in place, then the second phase commences, and the computation of the handicap begins. It is now necessary to set up the dials of the counter T to indicate the total for the ten panels on the board.

The dials of the counter T are constructed with friction-tight rims like the rim 10a (see Fig. 4) with flanges 44 that can be reached at the rear of the board. This enables the counter dials to be quickly and immediately set to indicate the proper total without having to carry over to the ten's and hundred's dials from the unit dial. The handicap for the total indicated will then be computed arithmetically, and the dials of the handicap indicator should be set up in the same manner as the counter dials through the agency of their flanges 45. The apparatus is now ready for its daily control.

Suppose for example, that the eleventh score 20 of the golfer is eighty-eight. A panel 4 with the number 88 on it, would then be pushed against the extreme right-hand panel 4 of the player's row, pushing out the extreme left panel 4 bearing the number 85. This, of course, would add 25 three to the player's total score for the last ten games. Just before shifting the panels 4 to the left in this way, the window 9 would show a number 85 on the dials 10 and 11 of the single game indicator. It is therefore necessary for the 30 operator of the apparatus to add three to the total score set up on the counter T. In order to accomplish this, the thumb head 20 would have to be rotated forwardly through three divisions; for example, rotating the dial 11 in a clockwise direction until the number 8 appeared in the window instead of the number 5. This advance movement would be imparted through the clutch 24, 25, to the unit dial 12 of the counter, and through the tubular sleeve 27 the pinion 29 10 would be rotated so as to pass on this change in the total to the handicap computer H.

Whenever it is desired to rotate the dials 10 and 11 independently of the counter, this can be done by pulling the thumb-head 20 in an outward direction. This shifts the tubular sleeve 21 toward the right, and opens the clutch 24, 25. The wheel 11 can then be rotated by means of the thumb-head through the slot 22 and pin 23 connection. The rim 10a on the dial 10 can be rotated by means of its knurled flange 10c, to set up any number desired on this dial without rotating the body of the dial which, of course, would be locked against rotation by engagement of its gear teeth at 34 with the teeth of the six-pointed gear portion of the carrier wheel 18.

When it happens that the player's presently made score is less than the first of his last ten scores, then the counter must have the difference subtracted from the total instead of added as in 60 the above example.

Many other embodiments of the invention may be resorted to without departing from the spirit of the invention.

What I claim is:

65 1. In apparatus for indicating a player's handicap, the combination of a single score counter having dials for indicating the score of the player in the last game played, a total counter having dials indicating the total score of the player for a certain number of selected games including the score of the last game played on which the handicap is based, hand-operated means for actuating both said counters to add to, or subtract therefrom, the difference between the player's presently made score and the score of the said last

game played, a handicap counter, and means for driving the handicap counter from the total counter at a reduced drive ratio based on the method of computing the handicap so that the handicap indicator indicates the correct handicap based on the number of selected games including the said presently made score.

2. In apparatus for indicating a player's handicap, the combination of a total counter having dials thereon indicating the total score of the player for a certain number of selected games including the score of the last game played on which the handicap is to be based, a single score counter having dials indicating the score of the player in the last game played on which the 15

handicap is to be based; said single score counter having a units dial, a clutch connecting the same to the units dial of the total counter for moving the units dial of the total counter forward or back, depending upon the amount of the presently made score of the player; said single score counter including a tens dial capable of movement independently of the units dial for setting up the player's last score on the same in cooperation with the said units dial of the single score counter, a handicap counter, and means for driving the same from the total counter at a reduced ratio.
